UNITED STATES PATENT OFFICE

103,707

DESIGN FOR A SHOE

Leander T. Carey, Medford, Mass., assignor to Colella & Leighton Shoe Company, Lynn, Mass.,
a corporation of Massachusetts

Application December 24, 1936, Serial No. 66,743

Term of patent 3½ years

To all whom it may concern:

Be it known that I, Leander T. Carey, a citizen of the United States, residing at Medford, in the county of Middlesex and Commonwealth of Massachusetts, have invented a new, original, and ornamental Design for a Shoe, of which the following is a specification, reference being had to the accompanying drawing forming a part thereof, in which

Fig. 1 is a plan view of a shoe, showing my new design; and

Fig. 2 is a side elevational view of the same.

I claim:

The ornamental design for a shoe substantially as shown.

LEANDER T. CAREY,
